UNITED STATES PATENT OFFICE

2,670,803

CHARGE FOR FIRE EXTINGUISHERS

Sidney B. Anderton and Eric E. C. Cawood, Elland,
England, assignors to Nu-Swift, Limited, Elland, England

Application June 7, 1951, Serial No. 230,286

6 Claims. (Cl. 169—32)

1

The invention relates to fire extinguishers of the type in which a liquid is carried in a vessel or outer container having a discharge outlet and within it (a) a sealed cartridge or equivalent container filled with a compressed or a liquefied gas or with a gas-generating charge the release or the functioning of which, as the case may be, is operative to effect discharge of the liquid from the outer container, and (b) a hermetically-sealed inner container filled with a foam-producing or other agent, the arrangement being such that when the gas charge is released or generated it functions by its pressure to unseal the foam-producing or other agent and to propel such agent forcibly into the liquid in the outer container and to admix it intimately therewith before effecting any material discharge of the liquid from the extinguisher.

The inner container, in which the foam-producing or other agent has been carried has been made of metal, and as such agents are usually of such a nature as to attack and corrode ordinary metals it has been necessary to make the said inner container of a special non-corrodible metal, which has made the extinguisher, or rather the charge for an extinguisher, very expensive to produce.

According to the present invention it is proposed to construct the inner container, in which a foam-producing or other agent is to be carried, from a flexible inert plastic material. Such a container can be made of sufficient wall thickness to enable it to be handled when filled without fear of breakage but such that when in position within an extinguisher it will be ruptured by the release or generation of the gas charge and its contents rapidly admixed, by the pressure of the released or generated gas, with the liquid in the outer container of the extinguisher.

The improved flexible inner container may be in the form of a tube closed at one end and adapted to be sealed at the other end after filling. It may, however, be of any other convenient shape or form.

The improved flexible inner container may be supported within the outer container in any suitable manner, in appropriate relation to the gas cartridge or to the outlet from such cartridge in such manner that the pressure of the gas when released or generated can function to rupture it quickly and propel its contents forcibly into and admix them intimately with the water or other liquid in the outer container before effecting any material discharge of the liquid from the extinguisher.

2

In the accompanying drawings we have shown in

Fig. 1 more or less diagrammatically a fire extinguisher of the type to which the invention relates; and in

Fig. 2 in sectional elevation one good, practical form of a charge for such extinguisher embodying the invention.

In the drawings, *a* represents a tube, which will be hereinafter termed the charge tube and which may be made of suitable metal not necessarily non-corrodible. The upper end of the tube *a* is flanged outwardly as at *a'* to support a carrier ring *b*, and it is held in position within an outer container *c* by means of a head *d* which forms a closure to the open upper end of the tube.

Supported within the upper end of the tube *a* by being screwed into a central threaded opening in the carrier ring *b* is a container *e* for compressed or liquefied gas, sealed at its upper end by a disc *e'* adapted to be punctured by a piercer *f* operable from the exterior of the head *d*.

Below the gas container *e* there is provided within the tube *a* a pad *g* of resilient material such as spongy rubber, the upper side of such pad being furnished with a washer *g'* of suitable material against which the lower extremity of the gas container *e* can abut. The pad *g* has a central opening *g*² through it of suitable diameter.

The lower extremity of the tube *a* is closed by a plate *h* having a central opening *h*² of suitable diameter, and resting on this plate is a pad *i* of suitable resilient material such as spongy rubber.

Between the two resilient pads *g* and *i* there is confined a sealed bag *j* composed of a flexible inert plastic material and adapted to contain a foam-producing or other agent, the said bag thus constituting as it were an inert lining to the portion of the tube *a* within which it is located. This is a feature of importance since the tube need not, if the agent with which the bag *j* is filled is of a corrosive nature, be made of non-corrodible and thus expensive metal.

When by the operation of the piercer *f* the sealing disc *e'* of the gas container *e* is punctured to release the gas charge the space *m* in the upper part of the tube *a* above the pad *g* becomes filled with pressure gas and the pad is forced downwardly to expose the central opening *g*² through the pad. The pressure gas thus passes into the space in the tube below the pad and compresses the flexible bag *j*. When the pressure on the bag becomes sufficiently great the resilient pad *i* beneath the bottom of the bag

is forced through the central opening h' of the plate h and the bag is forced into contact with the periphery of the opening h' and is thereby ruptured, the said periphery being preferably suitably serrated to assist in the rupturing of the bag.

When the bottom of the bag is ruptured the contents of the bag are discharged forcibly downwards into the liquid in the outer container of the extinguisher to become intimately admixed with it, and the liquid is expelled through the usual discharge pipe c' and foam producing nozzle c^2 .

The two resilient pads g and i are useful in protecting the flexible bag j during transport and the pad i serves the further useful purpose of delaying the rupture of the bag until a pressure has been developed above it sufficient to ensure rapid expulsion of the contents of the bag when rupture takes place.

Whilst the constructional embodiment of the invention which has been described and illustrated is good and practical and is preferred, it is only given by way of example as there are other ways in which the invention can be carried into practice. The lower end of the tube a might for instance be formed as an open-work grid and the flexible bag j rest directly upon such grid. Such an arrangement would not, however, provide protection for the lower end of the bag during transport, and there would be a risk of the openings in the grid becoming clogged on rupture of the bag by the material of which the bag is composed and thus preventing correct functioning of the extinguisher. In another arrangement the tube a might be perforated or reticulated say in its lower part in such manner that the pressure gas when released can force the bag into contact with the edges of the perforations or reticulations and thereby cause it to be ruptured. Neither of the alternative arrangements which have been mentioned present however the advantage of that which has been described and illustrated namely that the sealed flexible bag containing the foam-producing or other agent is protected against damage during transport.

Having thus described our invention, what we claim as new and desire to secure by Letters Patent is:

1. In a fire extinguisher, means for discharging under pressure a foam-producing or other agent into the main body of said fire extinguisher, comprising, in combination, a housing formed at one end thereof with an end wall formed with at least one opening therein communicating with the main body of said fire extinguisher; puncturing means arranged in said end wall; a sealed gas cartridge mounted in said housing; a flexible container loosely arranged in said housing between said gas cartridge and said end wall of said housing so as to be easily removable therefrom and being formed of a flexible material inert to the agent contained therein; and means for opening said gas cartridge, whereby the pressure of the gas released by said cartridge upon the opening thereof will force said flexible container against said end wall and thereby rupture said flexible container forcing the contents thereof through said opening in said end wall into the main body of said fire extinguisher.

2. In a fire extinguisher, means for discharging under pressure a foam-producing or other agent into the main body of said fire extinguisher, comprising, in combination, a housing formed at one end thereof with an end wall formed with

at least one opening therein communicating with the main body of said fire extinguisher; a sealed gas cartridge mounted in said housing; a flexible container loosely arranged in said housing between said gas cartridge and said end wall of said housing so as to be easily removable therefrom and being formed of a flexible material inert to the agent contained therein; puncturing means located on said end wall of said housing adjacent said opening therein; and means for opening said gas cartridge, whereby the pressure of the gas released by said cartridge upon the opening thereof will force said flexible container against said end wall and thereby rupture said flexible container forcing the contents thereof through said opening in said end wall into the main body of said fire extinguisher.

3. In a fire extinguisher, means for discharging under pressure a foam-producing or other agent into the main body of said fire extinguisher, comprising, in combination, a housing formed at one end thereof with an end wall formed with at least one opening therein communicating with the main body of said fire extinguisher; puncturing means arranged on said end wall; a sealed gas cartridge mounted in said housing forming a space between the side walls of said housing and said gas cartridge; a flexible container loosely mounted in said housing between said gas cartridge and said end wall of said housing so as to be easily removable therefrom and being formed of a flexible material inert to the agent contained therein; a resilient pad located between said gas cartridge and said flexible container and being formed with an opening contacting said gas cartridge which upon compression of said resilient pad allows said space between said side walls of said housing and said gas cartridge to communicate with said flexible container; and means for opening said gas cartridge, whereby the pressure of the gas released by said cartridge upon the opening thereof will force said flexible container against said end wall and thereby rupture said flexible container forcing the contents thereof through said opening in said end wall into the main body of said fire extinguisher.

4. In a fire extinguisher, means for discharging under pressure a foam-producing or other agent into the main body of said fire extinguisher, comprising, in combination, a housing formed at one end thereof with an end wall formed with a central opening therein communicating with the main body of said fire extinguisher; a sealed gas cartridge mounted in said housing forming a space between the side walls of said housing and said gas cartridge; a flexible container loosely arranged in said housing between said gas cartridge and said end wall of said housing adjacent said side walls thereof so as to be easily removable therefrom and being formed of a flexible material inert to the agent contained therein; puncturing means located on said end wall of said housing adjacent said opening therein; a resilient pad located between said gas cartridge and said flexible container and being formed with an opening contacting said gas cartridge which upon compression of said resilient pad allows said space between said side walls of said housing and said gas cartridge to communicate with said flexible container; and means for opening said gas cartridge, whereby the pressure of the gas released by said cartridge upon the opening thereof will force said flexible container against said end wall and thereby rupture said flexible container forcing the contents thereof through said

opening in said end wall into the main body of said fire extinguisher.

5. In a fire extinguisher, means for discharging under pressure a foam-producing or other agent into the main body of said fire extinguisher, comprising, in combination, a housing formed at one end thereof with an end wall formed with a central opening therein communicating with the main body of said fire extinguisher, said end wall being formed with a serrated puncturing portion adjacent said central opening therein; a sealed gas cartridge mounted in said housing forming a space between the side walls of said housing and said gas cartridge; a flexible container loosely arranged in said housing between said gas cartridge and said end wall of said housing so as to be easily removable therefrom and being formed of a flexible material inert to the agent contained therein; a resilient pad located between said gas cartridge and said flexible container and being formed with an opening contacting said gas cartridge which upon compression of said resilient pad allows said space between said side walls of said housing and said gas cartridge to communicate with said flexible container; a second resilient pad located between said end wall of said housing and said flexible container separating said flexible container from said end wall; and means for opening said gas cartridge, whereby the pressure of the gas released by said cartridge upon the opening thereof will force said flexible container against said end wall and thereby rupture said flexible container forcing the contents thereof through said opening in said end wall into the main body of said fire extinguisher.

6. In a fire extinguisher, means for discharging under pressure a foam-producing or other agent into the main body of said fire extinguisher, comprising, in combination, a housing formed at one end thereof with an end wall formed with an

opening therein communicating with the main body of said fire extinguisher; a sealed gas cartridge mounted in said housing forming a space between the side walls of said housing and said gas cartridge; a flexible container loosely arranged in said housing between said gas cartridge and said end wall of said housing adjacent said side walls thereof so as to be easily removable therefrom and being formed of a flexible material inert to the agent contained therein; puncturing means located on said end wall of said housing adjacent said opening therein; a resilient pad located between said gas cartridge and said flexible container and being formed with an opening contacting said gas cartridge which upon compression of said resilient pad allows said space between said side walls of said housing and said gas cartridge to communicate with said flexible container; a second resilient pad of sponge rubber located between said end wall of said housing and said flexible container separating said flexible container from said end wall; and means for opening said gas cartridge, whereby the pressure of the gas released by said cartridge upon the opening thereof will force said flexible container against said end wall and thereby rupture said flexible container forcing the contents thereof through said opening in said end wall into the main body of said fire extinguisher.
